(57) **CLAIM**

The ornamental design for an electronic acoustic device, as shown.

DESCRIPTION

FIG. 1 is a front view of an electronic acoustic device, showing my new design.

FIG. 2 is a rear view of the electronic acoustic device.

FIG. 3 is a right side view of the electronic acoustic device.

FIG. 4 is a left side view of the electronic acoustic device.

FIG. 5 is a top view of the electronic acoustic device; and,

FIG. 6 is a bottom view of the electronic acoustic device.
